DESIGN FOR A RECEPTACLE

Abraham Singer Karper, Brooklyn, N. Y.

Application January 25, 1936, Serial No. 60,805

Term of patent 7 years

To all whom it may concern:

Be it known that I, Abraham Singer Karper, a citizen of the United States, residing in the city of Brooklyn, county of Kings, and State of New York, have invented a new, original, and ornamental Design for a Receptacle, of which the following is a specification, reference being had to the accompanying drawing, forming part thereof.

Fig. 1 is a top plan view of the receptacle, showing my design;

Fig. 2 is a front elevational view, and

Fig. 3 is a side elevational view.

I claim:

The ornamental design for a receptacle, as shown.

ABRAHAM SINGER KARPER.
